UNITED STATES PATENT OFFICE.

WILLIAM I. CLAIBORN, OF CROCKER, MISSOURI.

COLLAPSIBLE CRATE.

1,158,984.

Specification of Letters Patent.

Patented Nov. 2, 1915.

Application filed September 3, 1913. Serial No. 787,905.

To all whom it may concern:

Be it known that I, WILLIAM I. CLAIBORN, citizen of the United States, residing at Crocker, in the county of Pulaski and State of Missouri, have invented certain new and useful Improvements in Collapsible Crates, of which the following is a specification.

The present invention relates to new and useful improvements in shipping crates.

There has been a long felt want among wholesalers, retailers, and all class of merchants for a simply constructed shipping crate which may be collapsed into folded form, may be cheaply manufactured, and will be of sufficient strength to withstand the wear and tear of transit. For the most part, however, the structures of this type which have been reduced to practice are of such complicated nature that the cost of manufacture is prohibitive, and the various folded parts so disposed that the liability of breakage is paramount. Being cognizant of the above conditions, the crate of the present invention has been designed with such regard to number, proportion and arrangement of parts that it may be cheaply manufactured, will be durable and efficient in its action, and may be readily collapsed to assume the form of a flat board or plank, so that when the crates have reached their destination and the contents have been removed, they may be readily folded to occupy a minimum amount of space in the return shipment.

An object of equal importance with the foregoing resides in the provision of a crate of the class described which may be readily and efficiently employed in shipping poultry, small live stock, such as sheep or hogs, vegetables, eggs or sacks of grain and the like.

The above and additional objects are accomplished by such means as are illustrated in the accompanying drawings, described in the following specification and then more particularly pointed out in the claim which is appended hereto and forms a part of this application.

With reference to the drawings, wherein I have illustrated the preferred embodiment of my invention as it is reduced to practice, and throughout the several views of which similar reference numerals designate corresponding parts, Figure 1 is a side elevation of the crate with the various foldable elements in open assembled relation; Fig. 2

is an end view; Fig. 3 is a bottom plan view with the various elements of the crate in folded position; and Fig. 4 is an edge elevation of the crate with the parts in folded relation.

Proceeding now to the description of the drawings, the numeral 10 designates the bottom wall or floor of the crate which, in the preferred embodiment, is rectangular in shape and is formed from pine or similar cheap wood. In this connection, it is, of course, obvious that the shape of the bottom wall 10, as well as the material from which it is made, is a purely arbitrary matter, and one which will be governed entirely by the purpose for which each batch of crates is to be employed. If found desirable, the bottom wall 10 may be square, and may be constructed of any suitable composition, such as compressed paper and the like.

The floor or bottom wall 10 carries four corner posts which are individually designated by the numerals 11, 12, 13 and 14. These posts are pivotally attached at their lower ends to the four corners of the member 10 by hinge rods, indicated at 15 and 16. Formed on the floor 10 at one extremity thereof or secured to the floor in any suitable manner, is an upstanding cleat 10' extending transversely between the filling strips 19 and 20, and preferably secured to the floor at the opposite extremity thereof is an upstanding cleat 10'' which is also arranged transversely of the floor. The cleats 10' and 10'' receive the intermediate portions of the rods 15 and 16 respectively and serve to connect the said rods with the floor. The corner posts 11 and 12 are arranged at one terminal of the member 10, while the members 13 and 14 are arranged at the opposite corners of the other terminal of the member 10. In pivoting the lower terminal of the corner posts 11 and 12 to one terminal of the member 10, a portion of each corner 100 has been cut-away, as indicated at 17 and 18, so that by arranging filling strips 19 and 20 on the longitudinal edges of the member 10, the outer face of the lower terminals of the members 11 and 12 will be in longitudinal 105 alignment with the lowermost steps 21 and 22 which are formed on the inner faces of the posts 13 and 14. In this connection, it is to be noted that a number of these steps are cut on the inner faces of the members 110 13 and 14 to receive the terminals of the pivoted slats 23 which form the side walls of

the crate. The outer faces of the corner posts 11 and 12 are stepped, as indicated at 24 and 25, respectively, for a similar purpose.

5 It will be apparent upon reference to Fig. 3 particularly that by thus stepping the inner faces of the posts 13 and 14 and the outer faces of the posts 11 and 12, the corresponding steps of the posts 11 and 13 and 10 12 and 14 are arranged in longitudinal alinement and are comprehended in the same longitudinal plane. The terminals of the side wall slats 23 are pivotally secured by bolts, rivets, or any other suitable fastening devices 15 26 at points approximately in the center of the various steps. It will be noted upon reference to Fig. 3 particularly that the slats 23 of each side of the crate are successively disposed in greater spaced relation from the filling strips 19 and 20, the obvious purpose of this construction being to permit the corner posts 11, 12, 13 and 14 to be folded, and at the same time making it possible to hold the side wall slats 23 so 20 25 that all of these elements will lie in the plane of the bottom wall 10, thus producing the plank like conformation of the crate when its elements are in collapsed position.

The hinge rods 15 and 16, upon which the 30 corner posts 11, 12, 13 and 14 are pivoted to the member 10, are preferably arranged with their terminals embedded in the corner posts. For this purpose recesses 27 are formed in the lower terminals of the corner 35 40 posts to receive the burs or nuts 28 which are threaded on the ends of the hinge rods for an obvious purpose.

As a means for holding the corner posts in vertical position when the crate is packed, 45 there has been provided a pair of retaining rods indicated at 29 and 30. These retaining rods 29 and 30 are equipped at one terminal with eyelets 31 which receive pivot studs or pins 32. These studs 32 are secured to the spacing strips 19 and 20, as will be readily observed upon reference to Fig. 2. The free terminals of the retaining rods 29 and 30 are formed with hooks, indicated at 33. It will be obvious upon reference to 50 Fig. 1 particularly that by applying the hooks 33 to the keeper eyelets 34 which are carried by the corner posts 11 and 12, the downward swinging movement of the corner posts into folded position is prevented, and 55 the various elements of the crate are firmly held in open position.

In order to bring the outer edges of the uppermost side wall slats, indicated at 35 and 36, into longitudinal alinement with the outer faces of the posts 13 and 14, their terminals, which are secured to the posts 13 and 14 have been cut-away as indicated at 37 and 38. The ends of the crate are closed by slats which are indicated at 39 and are 60 65 applied to the corner posts by nails, screws,

rivets, bolts or any other suitable or desired fastening means.

The upper wall or top of the crate consists of a plurality of transversely extending slats indicated at 40. These slats 40 are secured to the uppermost side wall slats 35 and 36 by any suitable fastening devices. The upper terminals of the corner posts 11 and 12 are connected by a bar 41, the terminals of which are bifurcated to receive tenons formed on the upper faces of the members 11 and 12. Bolts, rivets, or other suitable fastening devices are passed through the terminals of the bar 41 and through the tenons of the members 11 and 12 for an obvious purpose. 70 75 80

In order to adapt the crate for the shipping of poultry or small live stock, such as sheep or hogs, there has been provided a small sliding door which is indicated at 42 and consists essentially in a board which is 85 90 95 100 105 110 115 120 125 130

slidable transversely on the top of the crate. The terminals of this board 42 are normally disposed in closed position on the upper edges of the members 35 and 36, and are held against upward movement by retaining strips 43 and 44. As a means for limiting the sliding movement of this member 42, there has been provided a stop strip 45, the terminals of which are secured to the adjacent closure slats 46 and 47. A co-acting stop strip 48 has been secured to the upper face of the member 42 and obviously limits the sliding movement of this member 42 by engagement with the members 43 and 45, as will be most clearly apparent upon reference to Fig. 2.

From the foregoing, the manner in which the elements of the crate are manipulated when it is desired to open or fold the crate 105 will be obvious.

In conclusion, it is desirable to emphasize the fact that the crate of the present invention is peculiarly simple in construction and occupies when in folded position a minimum compass, thus imparting to it special value inasmuch as a number of the crates may be returned in a minimum storage space after they have reached their destination and their contents have been removed. 110 115

In reduction to practice, I have found that the form of my invention, illustrated in the drawings and referred to in the above description as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claim.

In line with the above statement, it may be well to note that one of the variations

which may be resorted to in the employment of this invention is the use of the device as a collapsible cradle. It is obvious from the foregoing description that the crate could 5 be readily employed in this manner, and would be particularly efficient inasmuch as it could be quickly folded and placed in a closet, drawer, or any other out-of-the-way place.

10 If desired, the crate of this invention might be removably mounted on a wheeled truck to provide a baby carriage. When the crate is thus used, it will be apparent that the body of the carriage can be readily 15 removed and folded to permit the storage of the vehicle in a minimum space.

What I claim is:

In a device of the character described, a floor, upstanding filling strips carried by 20 the side edges of the floor, transversely extending upstanding cleats carried by the floor at the extremities thereof, a plurality of posts, a pair of hinge rods pivotally connecting said posts with the floor at the corners thereof, the said cleats bearing over the 25

said hinge rods and connecting the rods with the floor, a plurality of slats forming end walls and secured to the opposite corner posts at the terminals of the crate, a plurality of slats forming side walls and pivotally secured at their extremities to the longitudinally alined corner posts, a plurality of slats forming a closure for the crate and secured to the uppermost of the side wall slats, a pair of retaining rods pivotally secured to the inner faces of said filling strips and provided at their free extremities with hooks, and eyelets carried by a pair of corner posts, the hooks of said rods being detachably engageable with said eyelets for holding the side and end walls in open position and the said retaining rods and eyelets being disposed entirely within the crate.

30 35 40
In testimony whereof I affix my signature in presence of two witnesses.

WILLIAM I. CLAIBORN. [L. S.]
